(57) CLAIM

The ornamental design for a resume reference verification report as shown and described.

DESCRIPTION

The patent or application file contains at least one drawing executed in color. Copies of this patent or patent application publication with color drawing(s) will be provided by the Office upon request and payment of the necessary fee.

FIG. 1 is a right perspective view of the resume reference verification report showing my new design.

FIG. 2 is a left perspective view thereof;

FIG. 3 is a top view thereof;

FIG. 4 is a bottom view thereof;

FIG. 5 is a left view thereof;

FIG. 6 is a right view thereof;

FIG. 7 is a rear side view thereof; and,

FIG. 8 is a front side view thereof.
